FLUID REGULATOR AND CUT-OFF.

No. 311,747.

Patented Feb. 3, 1885.

UNITED STATES PATENT OFFICE.

JAMES T. HAMBAY, OF PITTSBURG, PENNSYLVANIA, ASSIGNOR TO GEORGE WESTINGHOUSE, JR., OF SAME PLACE.

FLUID REGULATOR AND CUT-OFF.

SPECIFICATION forming part of Letters Patent No. 311,747, dated February 3, 1885.

Application filed October 1, 1884. (No model.)

To all whom it may concern:

Be it known that I, JAMES T. HAMBAY, a citizen of the United States, residing at Pittsburgh, in the county of Allegheny and State of Pennsylvania, have invented or discovered certain new and useful Improvements in Fluid Regulators and Cut-Offs, of which improvements the following is a specification.

In the accompanying drawings, which make part of this specification, Figure 1 is an elevation, partly in section, of my improved gas regulator and cut-off. Fig. 2 is a similar view showing a modified form of valve. Fig. 3 is a sectional detail view of the valve-shaft in Fig. 2. Fig. 4 shows the slotted weight in elevation.

My invention relates to an improved valve and operating mechanism for the automatic regulation of the pressure of gas at the points of consumption as against an excessive pressure, and also for automatically cutting off the gas-supply when the pressure is reduced to a dangerous extent.

The object of my invention is to provide means whereby natural gas, which is charged into the mains at such a high pressure that it is nearly impossible to prevent leakage from the mains, may be supplied to houses, or other inclosed places where such leakage could collect in dangerous quantities, at such a low pressure that there is slight probability of the occurrence of any leakage; and my invention has also for its object the prevention of the escape of gas from open burners at which the flame has been extinguished by a reduction of pressure on the restoration of such pressure.

In general terms, my invention consists in the construction and combination of parts, substantially as hereinafter described and claimed.

The valve-case 1 is divided into two compartments or chambers, 2 and 3, by the diaphragm or partition 4, said chambers being connected with the inlet and outlet pipes 5 and 6, respectively, said pipes being screwed or otherwise attached to opposite sides of the case 1.

In the diaphragm or partition 4 are formed the openings 7 and 8, through which the gas

can flow from the inlet-chamber 2 to the outlet-chamber 3, and through these openings 7 and 8 passes the valve-rod 9, on which are secured the double-balanced valves 10 and 11, adapted to fit suitably-formed seats at the ends of said openings, as shown. The upper end 55 of the valve stem or rod extends through the stuffing-box 12 on the upper side of the valve-case, and the lower end of the rod fits into a suitable guide-opening, 13, in the lower side of the case.

To the upper end of the valve-rod, outside of the case, is attached the end of the short arm of the lever 14, pivoted to the standard 15, secured to the top of the case, as shown; and to the long arm of the lever, near its outer end, is adjustably attached the piston-rod 16, extending into the cylinder 17, and provided with a piston, 18, adapted to operate in said cylinder, which is connected to the inlet-pipe 6 by the T-coupling 19.

On the long arm of the lever 14 is placed the weight 20, provided with a vertical slot to allow the lever to move independent of the weight, which in certain positions of the lever rests upon a bracket, 21, secured to the top of the cylinder 17.

To the outer end of the long arm of the lever 14 is attached one end of a spring, 22, the opposite end of the spring being secured to a lug, 23, projecting from the bottom of the cylinder 17. This spring aids in the downward movement of the lever and piston after the former has been relieved of the weight 20, and the tension to which it is adjusted determines the minimum pressure necessary to move the piston and open the valves. The head of the cylinder 17 is perforated, as shown, to allow of the escape of the air above the piston during the upward movement of the piston.

The valve mechanism having been attached to the service-pipe, as above described, and the minimum and maximum pressures to be employed at the point or points of use having been determined, the spring 22 is so adjusted that its tension will be sufficient to hold the lever and piston at the lowest point of their movement until the minimum pressure is exceeded. The valve-stem 9 and piston-rod 16

are so connected to the lever 14 that when the piston 18 is at the lower or upper end of the cylinder the valves 11 or 10 will be held onto their seats, but when the piston is at or near the middle of its stroke the valves will be opened to the fullest extent; hence any movement of piston to either side of its central position will effect a partial or entire closing of the valves. The weight 20 is made of such a size and is placed at such a point on the lever 14 that it will prevent the lever and the piston connected therewith from being forced up from the position which said parts assume when the valves are open—*i. e.*, at or near the middle of the cylinder—unless the pressure of the gas should exceed the predetermined maximum pressure. When the pressure is less than the maximum but more than the minimum, the weight is supported by the bracket 21, which is arranged at such a height as to support the weight when the piston is at or below the middle of the cylinder, and is vertically slotted so as to permit the piston to freely move independent thereof between its middle and lowest positions.

It will be observed that as the valves are perfectly balanced the piston in its movements will not have to overcome the pressure of gas on the valves, and as the piston is attached to the long arm of the lever, slight pressures on the piston will easily move the valves. By making the valves balanced by having the pressure act on the long arm of the lever, the device can be delicately adjusted and will quickly respond to slight variations in pressure.

It will be seen from the above that variations of pressure above the maximum or below the minimum will effect the closing of the valves. When the valves are closed by high pressure, they will be opened by the action of the weight when the pressure is again reduced, but should they be closed by a reduction of pressure below the minimum—*i. e.*, the point at which the flame at some or all of the burners is extinguished—the valves will remain closed until the lever and piston are raised by some attendant, thus preventing any escape from the burners on the restoration of pressure.

In place of the valve mechanism shown, I may employ a plug-valve, 24, as shown in Fig. 2, the lever 14 being so connected to a crank arm of the stem of the plug-valve by the rod 25 that said valve will be open when the piston is at or near the middle point of its stroke.

The operation of the other parts of the device with a plug-valve mechanism is similar to that above described.

When it is desired to use the valve and operating mechanism shown in Fig. 1 as a regulator only to prevent excessive pressures, the lower valves, 11, and the stop 21 should be omitted, in which case the supply is cut off only when the pressure is above the maximum. 65

In lieu of either the double-balanced or the plug-valve described, any other suitable double-acting valve may be used, and by "double-acting valve" I mean one that is capable of being opened and closed by the movement 70 of the valve in either direction.

I claim herein as my invention—

1. In a system of two or more pipes for the supply and distribution, under different pressures, of fluids under pressure, a double-acting 75 valve for regulating and cutting off the supply from the high-pressure part of the system to the low-pressure part, in combination with a piston connected to said valve and subject to pressure from the low-pressure part of 80 the system, said parts being so arranged for conjoint operation that the valve is closed by an abnormal pressure and opened by a reduction to normal pressure, and is closed by a dangerous reduction of pressure, and held in 85 such closed position when the pressure is restored, substantially as set forth.

2. In a gas regulator and cut-off, the combination of double-balanced valves and a piston for operating said valves, said parts being 90 arranged in such relation to each other that the valves are closed by an abnormal increase of pressure and opened by a reduction to normal pressure, and are closed by a dangerous reduction of pressure, and held in such closed 95 position when the pressure is restored, substantially as set forth.

3. In a gas-regulator, the combination of balanced valves, a lever connected at one end to said valves, a cylinder having its piston 100 connected to the opposite end of said lever, and a weight mounted on the lever, substantially as set forth.

4. In a gas regulator and cut-off, the combination of a double-acting valve, a lever connected to said valve, a cylinder having its piston 105 attached to one end of said lever, a slotted weight mounted on the lever, a stop for supporting the weight, and a spring connecting the lever and cylinder, substantially as set 110 forth.

In testimony whereof I have hereunto set my hand.

JAMES T. HAMBAY.
